Filed July 21, 1967, Ser. No. 7,937

Term of patent 14 years

(Cl. D9—254)

FIGURE 1 is a perspective view showing the top and two sides of a box cover or similar article embodying my new design;

The broken line showing of the box in FIG. 1 is for illustrative purposes only.

I claim:

The ornamental design for a box cover or similar article, as shown and described.
